CLAIM

The ornamental design for a backpacker's liquid fuel stove, as shown.

DESCRIPTION

FIG. 1 is a perspective view of a backpacker's liquid fuel stove showing my new design from the front and top with the legs thereof unfolded to an open position; FIG. 2 is a perspective view thereof from the front and bottom;

FIG. 3 is a perspective view thereof from the front and top, with the legs thereof folded to a closed position; FIG. 4 is a bottom plan view thereof;

FIG. 5 is a left side elevational view thereof;

FIG. 6 is a front elevational view thereof;

FIG. 7 is a right side elevational view thereof;

FIG. 8 is a rear elevational view thereof; and,

FIG. 9 is a top plan view thereof.
